UNITED STATES PATENT OFFICE

170,305

PHYSICIAN'S EXAMINING TABLE

Earl W. Claus, Kirkwood, Mo., assignor to Shampaine Company, St. Louis, Mo., a corporation of Missouri

Application March 19, 1953, Serial No. 24,111

Term of patent 14 years

(Cl. D33—14)

To all whom it may concern:

Be it known that I, Earl W. Claus, a citizen of the United States, residing at the city of Kirkwood, county of St. Louis, State of Missouri, have invented a new, original, and ornamental Design for a Physician's Examining Table, of which the following is a specification, reference being made to the accompanying drawing, forming a part thereof, in which:

I claim:

The ornamental design for a physician's examining table, substantially as shown.

EARL W. CLAUS.
